CLAIM

The ornamental design for an illuminated pet tag, as shown and described.

DESCRIPTION

FIG. 1 is a front perspective view of an illuminated pet tag illustrating my new design;

FIG. 2 is a front perspective view of the design of FIG. 1 in an illuminated state;

FIG. 3 is a front view of the design of FIG. 1;

FIG. 4 is a back view of the design of FIG. 1;

FIG. 5 is a top view of the design of FIG. 1;

FIG. 6 is a bottom view of the design of FIG. 1;

FIG. 7 is a side view of the design of FIG. 1; and,

FIG. 8 is a side view of the design of FIG. 1.

The broken lines represent portions of the illuminated pet tag and form no part of the claimed design. In FIG. 2, the broken lines show illumination and form no part of the claimed design.

1 Claim, 4 Drawing Sheets
